(57) **CLAIM**

The ornamental design for a luminaire, as shown and described.

DESCRIPTION

FIG. 1 is a bottom perspective view of a luminaire showing our new design;

FIG. 2 is a side elevational view thereof, the opposite side being a mirror image;

FIG. 3 is an end elevational view thereof, the opposite end being a mirror image;

FIG. 4 is a bottom plan view thereof;

FIG. 5 is a top plan view thereof; and

FIG. 6 is a cross-sectional view thereof taken along section lines 6-6 in FIG. 2.

FIG. 7 is a bottom perspective view of a luminaire showing an alternative embodiment of our new design;

FIG. 8 is a side elevational view thereof, the opposite side being a mirror image;

FIG. 9 is an end elevational view thereof, the opposite end being a mirror image;

FIG. 10 is a bottom plan view thereof;

FIG. 11 is a top plan view thereof; and,

FIG. 12 is a cross-sectional view thereof taken along section lines 12-12 in FIG. 8.

Certain of the broken lines shown in FIGS. 1-3 and 5-6 represent suspension cables, a ceiling canopy, and cable attachments; the broken line circles shown in FIGS. 1 and 4 represent auxiliary area light sources such as LEDs. The suspension cables, a ceiling canopy, cable attachments and auxiliary area light sources form no part of this embodiment of our claimed design.

Certain of the broken lines shown in FIGS. 7-9 and 11-12 represent suspension cables, a ceiling canopy, and cable attachments; the broken line rectangles shown in FIGS. 7 and 10 represent primary area light sources such as OLEDs; and the broken line circles shown in FIGS. 7 and 10 represent auxiliary area light sources such as LEDs. The suspension cables, a ceiling canopy, cable attachments, primary light sources and auxiliary area light sources form no part of this embodiment of our claimed design.
